UNITED STATES PATENT OFFICE

RALPH E. SMITH, OF GALION, OHIO, ASSIGNOR TO THE GALION METALLIC VAULT COMPANY, OF GALION, OHIO, A CORPORATION OF OHIO

DESIGN FOR A GRAVE-VAULT HANDLE

Application filed August 15, 1930. Serial No. 36,673. Term of patent 7 years.

To all whom it may concern:

Be it known that I, RALPH E. SMITH, a citizen of the United States, residing at Galion, in the county of Crawford and State of Ohio, have invented a new, original, and ornamental Design for a Grave-Vault Handle, of which the following is a specification, reference being had to the accompanying drawing, forming a part thereof.

In the accompanying drawings:

Figures 2 and 3 are sections showing the contour of the article.

I claim:

The ornamental design for a grave vault handle, substantially as shown.

RALPH E. SMITH.
